FINGER RING

John L. Hazelquist, Garden City, Mich., assignor to Traub Manufacturing Company, Detroit, Mich., a corporation of Michigan

Filed Feb. 4, 1963, Ser. No. 73,413

Term of patent 14 years

(Cl. D45—10)

FIGURE 1 is a perspective view of a finger ring showing my new design;

FIGURE 2 is a top plan view thereof with the broken line showing of the gem omitted therefrom for convenience of illustration;

FIGURE 3 is a left side elevational view thereof;

FIGURE 4 is a front elevational view thereof; and

FIGURE 5 is a right side elevational view thereof.

The band is continuous and has been shown partially in broken lines for convenience of illustration.

The essential features of the design reside in the stone setting.

I claim:

The ornamental design for a finger ring, as shown and described.
